CLAIM

The ornamental design for a collection device, as shown and
described.

DESCRIPTION

FIG. 1 is a top, left, and front perspective view of an
embodiment of a collection device, showing our new design;
FIG. 2 is a top, right, and front perspective view thereof;
FIG. 3 is a front elevation view thereof;
FIG. 4 is a back elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a bottom, left, and front perspective view thereof;
and,
FIG. 10 is a bottom, right, and front perspective view
thereof.

The broken lines illustrate portions of the collection device
which form no part of the claimed design.

1 Claim, 8 Drawing Sheets
